UNITED STATES PATENT OFFICE

2,525,854

DUSTPROOF PENCIL SHARPENER

Louis Becker, Ardmore, Okla.

Application March 8, 1946, Serial No. 652,856

1 Claim. (Cl. 120—93)

1

This invention relates to improvements in dust-proof pencil sharpeners having ample space for pencil shavings and dust including a collecting receptacle in combination with a baffle to prevent the spilling of the shavings and the dust through the sharpener while it is being handled and used by the operator or user thereof.

It is a particular object of this invention to provide a unique combination of a frusto-conical hopper and baffle with an attachable and detachable shavings and dust collecting receptacle.

It is an object of this invention to provide a combined hopper and shield baffle having a pencil sharpener therein in combination with a collecting receptacle for the shavings and dust in which the receptacle is detachably connected to the pencil sharpener.

Other objects and advantages will be revealed in connection with the detailed description of the accompanying drawings which constitute a part of this specification.

In the drawings:

Figure 1 is a longitudinal sectional view of my new dust-proof pencil sharpener.

Figure 2 is a transverse sectional view of my sharpener taken on the line 2—2 of Figure 1, looking in the direction of the arrows.

Figure 3 is an elevational view of one member of my sharpener having parts broken away and parts in section to clearly show features of its particular construction.

Figure 4 is a view in side elevation of the detachable receptacle used in the construction of Figure 1, and

Figure 5 is a side elevational view of a modified form of my invention having portions broken away and portions in section to clearly show the modified features of this invention.

Figure 6 is a detail edge view of a modified form of blade.

Figure 7 is an end elevational view of the structure shown in Figure 6.

Figure 8 is a perspective view of a modified form of my pencil sharpener.

The drawing is merely illustrative of my invention and is not definitive thereof except as pointed out in the subjoined claim.

In the drawing and specification the reference characters identify the details of my particular pencil sharpener.

The pencil sharpener 1 is provided with a main tubular cylinder 2 having a cap 3 preferably having a screw-threaded connection 4 with the main cylinder 2. The lower end of the cylinder 2 is provided with a detachable receptacle 5 having

2

telescopic relation with the main cylinder 2 and is also provided with a bottom wall 6 and an annular cap rim 7 having preferably a screw-threaded connection 8 with the cylinder 2. The receptacle 5 also constitutes a tubular cylinder and extends upwardly within the cylinder 2 beyond its mid-portion to provide an amply large removable receptacle for shavings and dust. The upper end of the cylinder or tube 2 is provided with a fixed apertured closure plate 9. The closure plate 9 has a centrally located aperture larger than an ordinary pencil (not shown) adapted to receive a tubular pencil guide 11.

The combined pencil sharpener and hopper-baffle constitutes a replaceable unit R.

This unit R comprises a hollow frusto-conical shell 12 with a cylindrical tubular portion 13 having a circular closure 14. The closure plate 14 may be secured to the cylindrical tube 13 by brazing, soldering, or welding. A pencil sharpener element 15 comprised of a tubular pencil guide 11 and a tapered portion 15 is secured in a pencil aperture in the closure 14 by screw threads 16. The tapered frusto-conical portion 15 including the blade slot 17 and the blade 18 extend downwardly into the frusto-conical hopper-baffle 12 and terminate substantially flush with the lower edge thereof. The blade 18 is secured to the tapered portion 15 by screws 20.

In order to place the unit R in position at the top of the hollow cylinder 2, the receptacle 5, 6, 7 must be removed from the cylinder 2 and the unit R may then be guided to position in the tube or cylinder 2 and secured in position by screws 20.

It is noted in Figure 1 that the major portion of the tube 2 is reinforced by the telescopic receptacle 5 which is removably received and is telescopically guided into and out of the tube 2.

In order to sharpen a pencil (not shown) the cap 3 must be removed from the tube 2 and the pencil inserted and sharpened in the usual manner. Instead of grasping the pencil sharpener 15 directly the tube 2 is grasped in one hand and relative rotation in the proper direction of the pencil and sharpener sharpens the pencil. It appears to be self-evident that more accurate sharpening could be accomplished by manipulating the large grasping surface portion of the tube 2.

50 The shavings and dust from the pencil are guided by the hopper-baffle 12 into the receptacle 5.

If the device is tipped sidewise and even upside down the contents of the receptacle 5 merely slides along the receptacle and tube 2 to a posi-

tion back of the hopper-baffle 12 and does not spill out because of the presence of the hopper-baffle.

It is an important result that the dust does not under normal use, including handling, tipping or even carrying it about in a garment pocket, spill out of the sharpener.

The construction disclosed in Figure 5 is identical with that disclosed in Figure 1, except that the tubular cylinder 20 constitutes united cylinders 21 and 22. The cylinders are preferably connected by a screw-threaded portion 23. The lower cylinder 22 is preferably provided with an inwardly offset annular portion 24, on which the threads are formed, whereby the connection or joint may be smooth or substantially flush on its outside of the sharpener construction. In this modification, as shown in Figure 5, the tube is only reinforced at and about the connection, and is not reinforced; and is not reinforced over its entire bottom portion, as shown in the construction of Figure 1.

In Figure 5, the cylinder 22 constitutes the removable receptacle and comprises substantially one-half of the tubular cylinder 20-21. The unit R and the section 21 may be readily assembled and secured together, since the unit R is longer than the section 21.

The combined pencil sharpener and hopper-baffle unit constitutes another important feature of my invention, since this unit is detachably secured to the upper end of the cylinder 2. When the blade 18 becomes dull, the whole unit can be replaced including a new blade.

The hopper-baffle 12 of Figs. 1 and 5 may be omitted.

As shown in Figures 6 and 7, the blade 18 may have a guard or shaving breaker in the form of a plate 28 mounted over the top of same. The forward edge 27 of the plate 28 breaks up the curled wood shavings as the blade 18 removes same from the pencil. The screws 19-19 of Figures 1 and 5 are here replaced by longer screws 29-29 having knurled heads.

Figure 8 shows a modified form of sharpener 30; adapted for use in either the cylinder 2 of Figure 1, or the cylindrical sections 21-22 of Figure 5 having a solid base 31 shaped like an inverted pyramid. The neck 32 rising from the base is closed by a suitable removable cap 33. After removal of this cap the neck can be fitted

in an opening in the top of a cylindrical cover 34 which is interiorly threaded for connection to a receptacle 35. Screws (not shown) may be passed through the top of the cover into holes 36 in the sharpener and below the neck.

Having fully disclosed my novel invention and the operation thereof, what I claim is:

A dust-proof pencil sharpener comprising a tubular receptacle, said receptacle being formed with upper and lower sections detachably connected together, the upper section including a closure member for the receptacle, said closure member having a central aperture therethrough, a pencil sharpener mounted in the upper end of said receptacle and including a tubular portion projecting through said aperture in said closure member, a hollow frusto-conical blade-carrying portion extending downwardly from said tubular portion, said blade-carrying portion having a slot therethrough, and a blade mounted along one edge of said slot, and a hollow frusto-conical baffle member surrounding said frusto-conical blade-carrying portion and attached to said tubular portion, said frusto-conical member serving to prevent dust within the receptacle from escaping therefrom through said tubular portion, said pencil sharpener and said baffle member being formed as a unit, said unit being detachably connected to said closure member, and a cap member detachably engaged with the top portion of said receptacle and enclosing said tubular portion.

LOUIS BECKER.
